UNITED STATES PATENT OFFICE.

GEORGE A. RICKS, OF LA FAYETTE, INDIANA.

ELECTRIC IRONING DEVICE.

994,605.

Specification of Letters Patent. Patented June 6, 1911.

Application filed November 2, 1910. Serial No. 590,329.

To all whom it may concern:

Be it known that I, GEORGE A. RICKS, a citizen of the United States, and a resident of La Fayette, in the county of Tippecanoe and State of Indiana, have invented a new and Improved Electric Ironing Device, of which the following is a full, clear, and exact description.

In the use of movable tools where it is necessary to supply an electric current to these tools, a flexible conductor for conveying the current is necessary, and this conductor, if suspended from a ceiling or fastened to a side wall or other support, must be provided with sufficient slack to allow the free movement of the tool over the work or to its different points of application. This slack is always more or less a source of annoyance to the operator of the tool and quite frequently interferes with its operation, and due to this constant moving breaks at points where sharp ends occur or where kinks form in the conductor.

This invention relates to a new and improved form of device adapted to overcome the difficulties common with this class of tools; and the object of the invention is to provide a suitable support for a flexible conductor, and a new and improved means for protecting the conductor to keep it off the working surface and away from the tool, and at the same time to prevent any interference with the working of the tool. I attain this result by attaching to the tool a coiled spring surrounding the conductor and having the other end attached to a bracket mounted upon the working surface.

With the above and other objects in view, as will more fully hereinafter appear, the present invention consists in certain novel details of construction and arrangement of parts hereinafter fully described, illustrated in the accompanying drawings, and more particularly pointed out in the appended claims.

In the accompanying drawings, forming part of this specification, the reference characters of which indicate corresponding parts in the several figures,—Figure 1 is a perspective view showing a preferred embodiment of my invention applied to an electric sad iron; Fig. 2 is an elevation of a preferred form of bracket and attached devices; Fig. 3 is a longitudinal transverse sectional view through the bushing and coiled spring hereinafter more fully described; and Fig. 4 is a

detailed illustration showing a preferred means for attaching the spring to the tool.

Positioned upon an ironing-board 1, or other working surface, is mounted at one end 60 thereof a bracket 2. Said bracket comprises two clamping arms 3 and 4, into one of which is threaded a screw 5, whereby the bracket is firmly clamped to the ironing-board 1. Threaded into the upper portion 65 of the bracket 2 is an externally-threaded bushing 6, one end of which is flared outward to form a flange 7. Between the outer face of the bracket 2 and the flange 7 is an aperture 8, through which projects one end 70 of a coiled spring 9. This end is wrapped about the exterior of the bushing 6, whereby the coiled spring is held firmly in place. The coiled spring 9 fits within the bore 10 75 of the bushing, and, due to the fact that this spring is tightly wound, forms a practically rigid extension connecting the bracket with the tool 11.

In order to form a flexible connection between the coiled spring and the tool, the 80 end of the spring 9 is angularly bent to form a transverse eye 12. Inserted into the eye and about some member of the tool is some preferred form of flexible connection, as, for instance, the strap 13. As the ends of 85 this strap 13 are fastened together by some means, as, for instance, the buckle 14, which may be readily unfastened, a means is afforded whereby the tool may be disconnected from the coiled spring quite readily. 90

Attached to the tool 11 by any preferred form of electric contact 15, and passing through the bore of the spring 9, and also passing through the bore 10 of the bushing 6, is a flexible conductor 16, the other end 95 of which is attached to an electric socket 17 positioned on the wall or any other suitable place. This coil affords a protective coating or shell for the conductor without increasing the number of parts of the device. 100 It will thus be seen that the electric tool, in this case, the sad iron, may be readily moved about from place to place upon the ironing-board without in any way interfering with the conductor. In any position of the iron, 105 the conductor passes freely through the bore of the coiled spring, and as this conductor cannot double upon itself, there is no danger of the formation of kinks. Further, this coiled spring forms a smooth bearing 110 for the passage of the conductor, and the one bracket serves as a support not only for

the tension device between the tool and the support, but also affords a support for the conductor. Further, it will be noted that although the spring is within a bore of the bushing; yet, due to the fact that the end of the spring is attached to the outside of the bushing, the end of the spring does not in any way interfere with the movement of the conductor. Further, it will be seen that 10 the tool may be moved about in any position on the board. When moved close to the support, the coiled spring or shell will double up, but, due to the rigidity of the coil, will afford an easy curve to the conductor, or when it is moved away to the further ends of the working surface, the shell or spring will be elongated again, permitting the inclosed conductor to ride freely without the formation of kinks.

15 20 As many changes could be made in the above construction, and many apparently widely different embodiments of this invention could be made without departing from the scope thereof, it is intended that all matters contained herein in the above description, or 25 shown in the accompanying drawings shall be interpreted as illustrative and not in a limiting sense. It is also to be understood that the language used in the following 30 claims is merely intended to cover all the generic and specific features of the invention herein described, and all statements of the scope of the invention, which, as a matter 35 of language, might be used to fall therebetween, and that material, sizes and relativi-

ties of parts are non-essential, except as called for in the claims.

Having thus described my invention, I claim as new and desire to secure by Letters Patent:—

40

1. A bracket for an electric ironing device, adapted to be adjustably mounted on one end of an ironing board, a bushing in threaded engagement with said bracket, said bushing having a flanged end, a coiled 45 spring within said bushing and having an end fastened about said flange, and having the other end adapted to be adjustably fastened to an iron, and a flexible conductor passing through said coiled spring and leading 50 to said electric iron.

55

2. In combination, an electric ironing device, comprising a bracket adapted to be adjustably mounted on one side of a board, a bushing in threaded engagement with said bracket, said bushing having a flanged end, a coiled spring within said bushing and having one end fastened to said flange and having the other end adjustably fastened to an iron, a flexible conductor passing 60 through said coiled spring and leading to said iron, and a strap connecting said spring with said iron.

65

In testimony whereof I have signed my name to this specification in the presence of two subscribing witnesses.

GEORGE A. RICKS.
